Peter M. Wright City of New York

Sellers Patent

The vehicle referred to in these Sellers Patent and making part of the same containing a description in the words of the said Peter M. Wright himself of his improvement in the construction of a family Breast Mill.

To all to whom these presents shall come, Be it known that Peter M. Wright of the City of New York, has invented a new and useful construction of a family Breast Mill the property of which as follows are a full and exact description of the same. The description shall give will be as plain and explicit as the machine in all its parts is simple, for an description of which parts I refer to the drawings and references and at the foot of this specification lay down their names and which I claim, I shall proceed to describe in a few words the general shape of the same. The first of which are that the great arm of the machine which attacks these contrivances of mills whose motions are obtained by a multiplication of cog wheels and pinions is in my construction I think obviously avoided by the application of a crank spindle, to be shown by the multiplication of cog wheels and pinions the velocity of the stones are increased and of course the acting force diminished and a great quantity of grain ground but as these mills are not intended to grind for a fast velocity is not required neither does it follow that the flour is ground better but on the contrary is heated and becomes out of the injury of a good quality. In fact in a small degree any substance will admit of various qualities of action by the upright lever attached to the end of the working rod it is evident may be made of mill a lever of the hand a hand cloth or no lever at all by the direct action upon the working rod.

The radius of these spindles may be increased to a greater extent than in this present case and be sufficiently strong to bear at least one hundred pounds and what velocity may still be maintained by a lever of hand cloth without any diminution of power but nothing can be made

of which will be of any use for this purpose than a lever of hand cloth or a hand cloth for the working of all these and that this

various ways of frequent changes and propelling of the body both conduction to his Mental and physical powers as in the process of Horsing, Hunting, &c. Horsing, Horses are confined to the narrow limits of a track, therefore where the position of our man only ^{will} be sustained, but by lengthening the arms of the lever the exertion of power may be applied.

Another advantage in the construction is that the counterbalance of the fly wheel is dispensed with and as the expelling gas acts as a continual and equalizer of motion is obtained by the weight attached to the lever. In relation to the bolt it follows these advantages but in stead of a Horsing as common it is made in the form of a conical cylinder which insures a more regular motion as it goes through more times in making it may through as the bolt is small it may be broken in any manner either by hand or feet & for this may be said in relation to the App of the Spindle in combination with the regulator that its construction is simple and saves the Spindle weight for particular other things may be mentioned such as securing the Spindle upon ^{the} frame by regulating the bearing upon the joints of the Spindle and the means of conducting or letting the flow into the bolt all of which it is understood are sufficiently explained in the references and drawings. The character of the machine and device specified are to go together with its construction, the application of the crank spindle working and to bear the strain of the demand upon the head of the Spindle, the means of regulating and letting the flow into the bolt and the conical form of the

Spindle
